UNITED STATES PATENT OFFICE.

FRANK B. MARTIN, OF BATTLE CREEK, MICHIGAN, ASSIGNOR TO POSTUM CEREAL CO., LIMITED, OF BATTLE CREEK, MICHIGAN, A PARTNERSHIP ASSOCIATION LIMITED, OF MICHIGAN.

CARTON-FEEDING DEVICE.

1,096,310.

Specification of Letters Patent.

Patented May 12, 1914.

Application filed June 17, 1912. Serial No. 704,202.

To all whom it may concern:

Be it known that I, FRANK B. MARTIN, of Battle Creek, Michigan, have invented a new and useful Improvement in Carton-
5 Feeding Devices, which invention is fully set forth in the following specification.

The present invention relates to carton-feeding and shifting machines, and is particularly an improvement in the means for
10 shifting cartons from one supporting surface to another.

For the purpose of illustration, the invention is herein shown for shifting cartons from the feed conveyers or belts to the main carrier or conveyer which advances the cartons to the sealing mechanism.

Heretofore, in practice, the cartons have been shifted from one or more feed belts to the main carrier by reciprocating means,
20 with the result that cartons were shifted onto the main conveyer only when the reciprocating means were moving toward the main conveyer, there being no feed of the cartons onto the main conveyer when said reciprocating means moved back to their original position. Such a construction, besides being complicated, is comparatively slow in operation, and the object of the present invention is to provide a simple and
25 economical construction whereby the cartons are more rapidly fed from one or more feed belts onto the main conveyer, said invention involving the use of a rotating member which engages the cartons and shifts them laterally. A single shifting device may be employed, but, for the purpose of illustration, duplicate connected shifting devices are shown as applied to a machine provided with two feed belts, one shifting device being associated with each belt.

The invention will be better understood by reference to the accompanying drawings, wherein—

Figure 1 is a plan view showing the improved device in duplicate associated with two feed belts and a main conveyer; Figs. 2 and 3 are detail plan views showing different positions of the carton as it is laterally shifted; Fig. 4 is a transverse vertical section on the line A—A of Fig. 1; and Fig. 5 is a detached perspective view of duplicate connected shifting means.

Referring to the drawings, 6—6 are suitably mounted and driven feed belts which carry the filled cartons, and 7—7 are tracks

or ways on to which the cartons are shifted laterally by the improved means hereinafter described. Associated with tracks or ways 7—7 are followers 8—8, which are carried by any suitable conveying means, as endless chain 9. These followers engage the cartons and progress them in two streams to their desired destination, as the gluing and sealing devices.

On each side of the machine, there is mounted in a bracket 10, secured on the frame 11 of the machine, a vertical shaft 12. At its upper end, said shaft is provided with a beveled gear 16 which meshes with a beveled gear 17 mounted on a shaft 18, 70 which shaft is suitably supported at its ends in bearings on brackets 19 secured to the frame of the machine. Said shaft 18 is provided with a second beveled gear 20 identical with gear 17, and meshing with a beveled gear 21 identical with gear 16. It will therefore be appreciated that when power is applied, shafts 12 will rotate in opposite directions. Shafts 12 are driven by any suitable means, but, preferably, one end of shaft 18 is extended beyond bracket 19 and a gear wheel 15 is mounted thereon, a driving chain 14 passing around said wheel. Each shaft 12 is suitably provided with a plurality of arms 22, which rotate over its associated belt 6. A stationary stop 23, adjustable in a bracket 24 (Figs. 1 and 5), suitably secured to the frame of the machine, is associated with each shaft 12, and, as here shown, said stop is provided with two arms 25 and 26, the ends of which are bent at right angles to project over the adjacent feed belt 6; and the arms 22 rotate between said arms 25 and 26. The rotation of shafts 12 is timed with the movement of conveyer 9, 95 so that the followers 8 will be in proper position to engage the cartons as they are laterally shifted from belts 6 onto tracks or ways 7.

The operation of the device is as follows: 100 The cartons are conveyed by belts 6 until said cartons in each stream successively engage the arms of stops 23 (Fig. 3), at which time one of the rotary arms 22 engages the carton and shifts it laterally from the belt 6 onto the track or way 7, along which it is progressed by reason of the engagement of follower 8 carried by conveyer 9. The operation of the device is identical on both sides of the machine.

The invention is as applicable to a single machine provided with only one feed belt as to a double machine, such as herein illustrated.

5 By the use of the construction above described, the sealing capacity of the machine is nearly double that attained by the use of the reciprocating shifting means.

What is claimed is:—

- 10 1. In combination, a supporting surface, means for moving objects along said surface, a movable conveyer arranged beside said surface, and traveling in the same direction as said means, a stationary stop associated with said conveyer, and a rotary device provided with a plurality of arms laterally shifting objects from said conveyer to said surface.
- 15 2. In combination, a supporting surface, means for moving objects along said surface, a movable conveyer arranged beside said surface, a two-armed stationary stop extending over said conveyer, a rotary device provided with a plurality of arms said arms passing between the arms of the stationary stop, and means for rotating said device.
- 20 3. In combination, a supporting surface, means for moving objects along said surface, a movable conveyer arranged beside said surface, and traveling in the same direction as said means, a stationary stop associated with said conveyer, a vertical shaft, a plurality of arms secured thereto, and means rotating said shaft whereby said arms laterally shift objects from said conveyer onto said surface.
- 25 4. In combination, a supporting surface, means for moving cartons along said surface, a movable conveyer arranged on each side of said surface, a rotary device provided with a plurality of arms associated with each conveyer, connections between said devices whereby they are rotated in opposite directions, and means for rotating said devices whereby cartons are shifted laterally from said conveyers onto said surface.
- 30 5. In combination, a supporting surface, means for moving cartons along said surface, a movable conveyer arranged beside said surface and traveling in the same direction as said means, a stationary stop associated with said conveyer, and a rotary device provided with a plurality of arms laterally shifting objects from one to the other.
- 35 6. In combination, a supporting surface, means for moving cartons along said surface, a movable conveyer arranged on each side of said surface, a stationary stop projecting over each conveyer, a rotary device mounted on a vertically disposed shaft and provided with a plurality of arms associated with each conveyer, said arms or wings rotating between the arms of said stop, connections between said devices whereby they are rotated in opposite directions, and means for rotating said vertically disposed shafts whereby cartons are shifted laterally from said conveyers onto said surface.
- 40 7. In combination, a supporting surface, means moving objects along said surface, a movable conveyer arranged beside said surface and traveling in the same direction as said means, a stationary stop associated with said conveyer, and a rotary device provided with a plurality of arms laterally shifting objects from one to the other.
- 45 8. In combination, a supporting surface, means moving objects along said surface, a movable conveyer arranged beside said surface and traveling in the same direction as said means, and a rotary device provided with a plurality of arms laterally shifting objects from one to the other.

face, a movable conveyer arranged on each side of said surface, a stationary stop projecting over each conveyer, a rotary device provided with a plurality of arms associated with each conveyer, connections between said devices whereby they are rotated in opposite directions, and means for rotating said devices whereby cartons are shifted laterally from said conveyers onto said surface.

6. In combination, a supporting surface, means for moving cartons along said surface, a movable conveyer arranged on each side of said surface, a stationary two-armed stop projecting over each conveyer, a rotary device mounted on a vertically disposed shaft and provided with a plurality of arms associated with each conveyer, said arms or wings rotating between the arms of said stop, connections between said devices whereby they are rotated in opposite directions, and means for rotating said vertically disposed shafts whereby cartons are shifted laterally from said conveyers onto said surface.

7. In combination, a supporting surface, means moving objects along said surface, a movable conveyer arranged beside said surface and traveling in the same direction as said means, a stationary stop associated with said conveyer, and a rotary device provided with a plurality of arms laterally shifting objects from one to the other.

8. In combination, a supporting surface, means moving objects along said surface, a movable conveyer arranged beside said surface and traveling in the same direction as said means, and a rotary device provided with a plurality of arms laterally shifting objects from one to the other.

In testimony whereof I have signed this specification in the presence of two subscribing witnesses.

FRANK B. MARTIN.
